UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 24,745, dated October 8, 1895.

Application filed September 3, 1895. Serial No. 561,375. Term of patent 3½ years.

To all whom it may concern:

Be it known that I, WILLIAM T. SMITH, a citizen of the United States, residing at Philadelphia, in the county of Philadelphia and State of Pennsylvania, have invented and produced a new and original Design for a Woven Fabric, of which the following is a specification, reference being had to the accompanying drawing, making a part of the same.

10 The leading feature of my design is a center panel, upon which is represented a bicycle

and a female figure. The panel is surrounded by a scroll and floral border.

Having, as above, fully described my invention, what I claim as new, and desire to secure by Letters Patent, is—

The design for a woven fabric, as shown and described.

W. T. SMITH.
